UNITED STATES PATENT OFFICE

2,422,468

ELECTROLYTIC PRODUCTION OF
PINACOLS

Thomas S. Chambers, Newark, and Ober C. Slotterbeck, Rahway, N. J., assignors to Standard Oil Development Company, a corporation of Delaware

Application July 4, 1942, Serial No. 449,718

6 Claims. (Cl. 204—77)

1

The present invention pertains to a method of preparing vicinal glycols by electrolytic reduction of ketones and generally to all types of carbon to carbon reductive condensation reactions.

Specifically, our invention is concerned with the reduction of acetone electrolytically to tetramethylethylene glycol.

It is the object of the present invention to provide the art with a novel and high advantageous method of electrolytically forming vicinal glycols and especially pinacols from the corresponding ketones, and also to provide the art with novel electrodes for effecting the reduction of organic compounds.

The electrolytic reduction of ketones can take place at the cathode surface according to any one of the following reactions:

Other side reactions result in the formation of metal alkyls, especially when the reduction is effected in acid medium with lead cathodes.

An electrolytic method for effecting the reductive condensation reaction whereby acetone is converted to pinacol (tetramethylethylene glycol) using a lead cathode and an acid catholyte is described in German Patent 113,719 (1899). The claims of the German patent were verified by Elbs in Z. Electrochemie, 7,644 (1901).

Several German patents pertaining to the electrolytic reduction of acetone to pinacol were issued in the period 1912-1920. Among these patents were DRP. 306,304 (1917), 306,523 (1918) and 324,919 (1920). The principal developments made in this period appear to have been the use of mixed metal and alloy cathodes, such as 4 to 10% copper—96 to 90% lead mixtures and 10% tin—90% lead alloy, and the use of horizontally suspended cathodes to prevent the metal alkyls formed from accumulating on and decreasing the activity of the electrode surface.

All of the prior processes for electrolytically converting acetone to pinacol have been unsatisfactory either because pinacol current efficiency or the overall current efficiency or both were too

low. The current efficiency (C. E.) is the ratio of the theoretical quantity of electricity required for a given reduction to that actually used. Thus, the % pinacol C. E.

$$5 = \frac{\text{grams of pinacol hydrate} \times 53.6 \times 100}{\text{mol. wt. of pinacol hydrate} \times \text{total ampere hours}}$$

We have now found that the formation of toxic lead alkyls which diminish the effectiveness of the cathode can be minimized and the reduction of ketones to vicinal glycols effected with good current efficiency and high ratio of glycols to other reduction products by utilizing as the cathode a low hydrogen overvoltage metal having a thin film of lead deposited thereon.

10 The ketones which may be treated in accordance with the present invention correspond to the general formula

wherein R stands for an alkyl or aryl radical or an alkyl or aryl radical substituted by a group 25 not reducible under the conditions covered by this invention, i. e., halogen, carboxyl, etc. Such ketones include, for example, acetone, methyl ethyl ketone, diethyl ketone, methyl propyl ketone, ethyl propyl ketone, acetophenone and 30 benzophenone.

By using mixtures of different ketones, it is possible to prepare certain mixed glycols. For example, acetone may be condensed with methyl ethyl ketone to form the glycol corresponding to 35 the formula

40 or methyl ethyl ketone may be condensed for example with acetophenone to form the glycol

45 The glycols formed in accordance with the present invention correspond to the general formula:

wherein each R stands for an alkyl or aryl radical or an alkyl or aryl radical substituted by a substituent such as halogen, carboxyl, etc.

Cells suitable for carrying out the reduction of ketones in accordance with the present invention are shown diagrammatically in the accompanying drawing.

Figure 1 is a plan view of a single unit cell and Figure 2 is a vertical cross-section of a multiple unit cell.

Figure 3 is an isometric view of the cathode of the present invention.

The single unit cell consists of a rectangular jar or the like 2, arranged in a cooling bath 1. An anode 3 of lead or the like is arranged inside an acid resistant diaphragm 4, which divides the cell into an anode and cathode compartment. As shown, two cathodes 5 of copper or other metal of low hydrogen overvoltage having a thin coating of lead are arranged in the cell.

In the multiple unit cell shown in Figure 2, 1 is a rectangular acid resistant tank; 2 are diaphragms which may be made of suitable acid resistant material; 3 are the lead coated cathodes, while 4 are the anodes which may be made of lead, carbon, or the like. 5 is a pump for circulating the catholyte; 6 are cooling coils for controlling the temperature of the electrolyte. The cooling fluid passing through coils 6 is circulated through line 7, cooling bath 8 and lines 9 by circulating pump 10. The details of the cell are not critical to our invention and the cell may be altered in numerous ways. For example, the process could be carried out continuously by providing a circulating pump, an overflow means for drawing off the catholyte from the cell, means for separating electrolysis products from the withdrawn catholyte and means for making the catholyte up to initial strength for reintroduction into the cell.

Figure 3 illustrating the electrode in accordance with this invention has part of the lead coating removed to show the base.

The use of a diaphragm is recommended since the products formed at the cathode are liable to be oxidized at the anode. The use of a diaphragm may be avoided if desired, however, by the use of anolyte and catholyte of unequal densities in cells provided with horizontal electrodes, by the use of a high anodic current density or by the use of anodes having a low oxygen overvoltage, i. e., nickel or by a combination of two or more of these expedients.

The metals of low hydrogen overvoltage that may be used as the base for our cathode include copper, nickel, silver, gold and platinum or alloys such as Monel metal and brass.

The film of lead is preferably electrodeposited on the low overvoltage metal base in the following manner: Plates of the metal which are to serve as the base of the cathode are treated for a few minutes with one part of nitric acid to three parts of distilled water. The plates are washed with water to remove nitric acid and are then ready for lead plating. The plating bath contains about 50 to 100 grams of lead nitrate per liter of distilled water. Lead sheets are used as the other electrodes and upon assembly of the cell, the plates which are to receive the lead plating are made the anodes and the lead sheet is made the cathode at a current density of about 1.55 amperes/sq. dm. for $\frac{1}{2}$ minute. The current flow is then reversed so that the plates are cathodes and the lead sheets the anodes. Plat-

ing is continued for about 2 minutes at the same or a higher current density. The lead coated plates are then removed from the plating bath and immediately washed with hot water and dried, whereupon they may be used directly without any further conditioning treatment. It is to be understood that this method of preparing our lead coated cathodes is merely illustrative and that other methods can be utilized. For example, the lead can be deposited on the base plates from fluosilicate, fluoborate and perchlorate baths. The important factor in the preparation of the cathode is that the lead deposit must be kept very thin, preferably within the range from about 0.02 to about 0.5 gram/sq. dm.

Aside from the nature of the cathode surface, the factor which has the greatest effect upon the course of the reaction in the cell is the concentration and type of electrolyte used. Acid media have given the best results. The ratio of ketone to water in the catholyte should be high. However, a ratio of 4/1 appears to be approximately the upper limit economically because of the high resistivity of the solution which would greatly increase the power cost. In the production of tetramethylethylene glycol the preferred catholyte is one containing about 4 volumes of acetone for each volume of sulfuric acid of about 20% strength. The acid, however, may vary in strength between about 15% and about 40%. It is noted that where reference to strength of sulfuric acid is made, it should be understood that the strength indicated is weight percentage.

The anolyte may be a sulfuric acid solution of about 15 to 40% strength. The electrolyte is preferably maintained at temperatures between about 0° C. and about 25° C. The current density applied may vary between about 0.1 and about 4 amperes/sq. dm., the preferred current density being within the range of about 1 to about 2 amperes/sq. dm.

The following examples serve to illustrate our invention but it is to be understood that our invention is not limited thereto.

Example 1

A single unit cell as shown in Figure 1 having a capacity of about 4 liters was provided with a lead anode. The cathodes were copper sheets about 21 x 20 cms. and about 0.2 cm. in thickness. The copper sheets were treated as described above and electroplated in a solution of lead nitrate containing 100 grams of lead nitrate/liter at 20 amperes for 2 to 3 minutes. The catholyte consisted of a 4/1 acetone 15-20% sulfuric acid solution. The anolyte was 20% sulfuric acid. The electrolysis was conducted at 0-10° C. at a current density of 1.55 to 2 amperes/sq. dm. The run was conducted for 21 hours.

Upon conclusion of the electrolysis, isopropyl alcohol and unreacted acetone were stripped from the catholyte under reduced pressure at low temperatures (below 25° C.). The pinacol (tetramethylethylene glycol) was separated from the residue as the hexahydrate by cooling and filtering the crystals.

656 grams of pinacol hydrate corresponding to 343 grams of tetramethylethylene glycol and 14 grams of isopropyl alcohol were obtained. This corresponds to an overall current efficiency of 44% based on pinacol and 3.6% based on isopropyl alcohol. The mol ratio of pinacol hydrate to isopropyl alcohol was 12.5/1.

When using 4% copper-96% lead, or 10% copper-90% lead mixtures in sheet form as the cath-

ode in lieu of the lead deposited on copper cathodes with 25% sulfuric acid anolyte and 4/1 acetone 25% sulfuric acid catholyte, electrolyzed at 16° C. at a current density of 1.67 amperes/sq. dm. for 6 and 5 hours respectively, current efficiencies based on pinacol of 12.7% and 13.8%, respectively, and a mol ratio of pinacol hydrate/isopropyl alcohol of 0.4/1 and 0.9/1, respectively were obtained.

Example 2

A multiple unit cell as shown in Figure 2 was operated in a semi-continuous manner. The anodes were of lead and the cathodes were copper sheets having a coating of lead weighing about 0.12 gram/sq. dm. electrodeposited thereon.

The catholyte was 4/1 acetone, 20% sulfuric acid and the anolyte was 25 to 40% sulfuric acid. The electrolysis was conducted at 10° C. and a current density of 1.0 amp./sq. dm. The lead coated copper cathodes were changed every 18 to 20 hours. The catholyte amounting to approximately 20 liters was circulated continuously from a glass receptacle through the cell and into a recycle receptacle over each 24 hour period. The recycle receptacle was maintained at a temperature about 10 to 20° C. below that of the cell, thereby continuously removing some pinacol hydrate (tetramethylethylene glycol hexahydrate) from the catholyte.

The data from the run is summarized in the following table:

Hour	Cathode Change No.	Ampere Hrs.		Tetramethyl ethylene glycolhexahydrate-g.		Isopropyl Alcohol Total grs.	Current Efficiency Based on Pinacol		Mol Ratio Pinacol/Isopropyl Alc.

¹ Readings and analyses were made at interval times stated.

What we claim and desire to secure by Letters Patent is:

1. In the process of producing glycols corresponding to the general formula

wherein R stands for a member of the group consisting of alkyl and aryl radicals and substituted alkyl and aryl radicals by the electrolytic reduction of an aqueous acid solution of a ketone of the formula

wherein R stands for a member of the group consisting of alkyl and aryl radicals and alkyl and aryl radicals substituted by a group which is not reducible under the reaction conditions employed, the improvement which comprises effecting said reduction at a temperature below about 25° C. and at a current density of between about 0.1 and about 4 amps./sq. dm. in a dia-

phragm cell in contact with a cathode comprising a sheet of copper, completely covered with a thin, electrodeposited layer of lead weighing from about 0.02 to about 0.5 gram/sq. dm.

2. In the process of producing glycols corresponding to the general formula

wherein R stands for a member of the group consisting of alkyl and aryl radicals and substituted alkyl and aryl radicals by the electrolytic reduction of an aqueous sulfuric acid solution of a ketone of the formula

wherein R stands for a member of the group consisting of alkyl and aryl radicals and alkyl and aryl radicals substituted by a group which is not reducible under the reaction conditions employed, the improvement which comprises effecting said reduction at a temperature below about 25° C. and at a current density of between about 0.1 and about 4 amps./sq. dm. in a diaphragm cell in contact with a cathode comprising a sheet of copper, completely covered with

a thin, electrodeposited layer of lead weighing from about 0.02 to about 0.5 gram/sq. dm.

3. The process as defined in claim 2 wherein the ketone and the sulfuric acid are used in the ratio of 4 volumes of ketone to one volume of acid.

4. The process of producing tetramethyl ethylene glycol by the electrolytic reduction of an aqueous acid solution of acetone, the improvement which comprises effecting said reduction at a temperature below about 25° C. at a current density of between 0.1 and about 4 amps./sq. dm. in a diaphragm cell in contact with a cathode comprising a sheet of copper, completely covered with a thin, electrodeposited layer of lead weighing from about 0.02 to about 0.5 gram/sq. dm.

5. The process of producing tetramethyl ethylene glycol by the electrolytic reduction of an aqueous sulfuric acid solution of acetone, the improvement which comprises effecting said reduction at a temperature below about 25° C. at a current density of between 0.1 and about 4 amps./sq. dm. in a diaphragm cell in contact with a cathode comprising a sheet of copper, completely covered with a thin, electrodeposited layer of lead

weighing from about 0.02 to about 0.5 gram/sq. dm.

6. The process as defined in claim 5 wherein the ketone and the sulfuric acid are used in the ratio of 4 volumes of ketone to one volume of acid.
